UNITED STATES PATENT OFFICE.

JONATHAN S. JONES, OF OAK PARK, ILLINOIS.

WEIGHING-SCALE.

1,363,253.

Specification of Letters Patent. Patented Dec. 28, 1920.

Application filed January 28, 1920. Serial No. 354,634.

To all whom it may concern:

Be it known that I, JONATHAN S. JONES, a citizen of the United States, residing at Oak Park, in the county of Cook and State of Illinois, have invented certain new and useful Improvements in Weighing-Scales, of which the following is a specification.

This invention relates to improvements in weighing scales, particularly adapted 10 though not necessarily limited in its use for weighing out predetermined quantities of material from a supply or bulk, and one of the objects of the invention is to provide an improved device of this character which will 15 be automatic in operation and which will continue to operate without the attention of the operator so long as the bulk or supply of material lasts.

A further object is to provide an improved device of this character having means 20 whereby the quantities measured out or weighed out may be varied at will.

A further object is to provide an improved device of this character which will be 25 simple, durable, cheap and compact in construction and effective and efficient in operation.

To the attainment of these ends and the accomplishment of other new and useful objects as will appear, the invention consists 30 in the features of novelty in substantially the construction, combination and arrangement of the several parts hereinafter more fully described and claimed and shown in 35 the accompanying drawings illustrating this invention, and in which:

Figure 1 is a side elevation of an improved device of this character with parts broken away.

40 Fig. 2 is a detail sectional view on line 2-2, Fig. 1.

Fig. 3 is a detail sectional view on line 3-3, Fig. 1.

Fig. 4 is a detail sectional view on line 45 4-4, Fig. 1.

Fig. 5 is a view similar to Fig. 1 showing the parts in a different position.

Fig. 6 is a right hand end elevation of Fig. 5.

50 Referring more particularly to the drawings, the numeral 10 designates a suitable supporting base having connected therewith suitable uprights 11 and which uprights support at any desired distance above the base

55 10, a suitable hopper 12 for containing the material to be weighed out. This hopper

may be of any desired size and configuration and is preferably provided with a discharge outlet 13 of a liberal size and a smaller discharge outlet opening 14, for a purpose to 60 be hereinafter set forth.

A suitable cut-off 15 is provided for controlling the outlet openings 13-14 and this cut-off is mounted preferably upon a swinging support 16 and is adapted to alternately 65 close the outlets 13-14 as the support 16 is shifted. The support 16 may be mounted for pivotal movement in any desired or suitable manner such as by means of pivot pins 17 connected with the wall of the hopper 12. 70 The support 16 preferably extends for a considerable distance below the hopper and adjustably mounted upon the support 16 is a receptacle or tray 18 which latter is adapted, when the outlet opening 13 is open, to assume a position therebelow to receive the material from the hopper 12. At the same time when the receptacle 18 is in this position, the cut-off 15 will assume the position 75 shown in Fig. 5 to close the outlet 14. 80

If desired, the receptacle 18 may be mounted for adjustment upon the support 16 in directions toward and away from the hopper by means of suitable adjusting mechanism embodying a screw or pin 19 co-operat- 85 ing with apertures 20 in the support 16. This adjustment is provided so that during a predetermined operation of the apparatus, a greater or less quantity of the material from the hopper will be delivered into the 90 receptacle 18 before the latter is dumped in a manner to be hereinafter set forth.

A scale beam 21 is pivotally and detachably connected with a support or upright 22 in any suitable manner such as by means of 95 a pin and keyhole slot connection 23-24. This scale beam is pivoted intermediate its ends, one end thereof being located adjacent the hopper while the other end 25 is provided with graduations 26 and with which 100 graduations an adjustable weight 27 co-operates. This weight is held in its adjusted position upon the scale beam by means of a suitable securing device 28 and if desired, a supplemental and adjustable weight or ele- 105 ment 29 may be connected with the weight 27 for the purpose of securing a fine adjustment of the weight with respect to the graduations 26 as is usual in devices of this character. Connected with the end of the 110 scale beam 21 which carries the graduations 26 is a counter-balance 30 preferably of sub-

stantially the configuration shown and this counter-balance is provided as a means for counter-balancing the mechanism and also as a means for returning the parts to a position 5 to receive the material from the hopper.

Connected with the end of the scale beam 21 which is adjacent the hopper 12 is a track or runway 31 which is preferably disposed at an angle to the scale beam. This 10 track or runway may be of any desired length and the extremity 32 thereof is deflected or offset so as to form a curved portion at the delivery end of the track, and arranged at the extremity of the track is a stop 33, while 15 a similar stop 34 is arranged at the opposite end of the track.

Mounted to move upon this track or runway is a car or traveling receptacle 35 having an open front end and provided with 20 uprights 36—37 respectively carrying the wheels 38—39. The uprights 36 are of a length somewhat greater than the length of the uprights 37 so that when the scale beam and parts are in the position shown in Fig. 25 1 the car or receptacle 35 will assume an inclined position toward the rear so as to prevent the material being delivered thereto from passing out of the open front end, but when the car travels upon the track or 30 way 31 toward the free end thereof, and as the scale beam moves about its pivot under the influence of the traveling movement of the car, it will be noted that the track or way 31 will be lowered and as it is lowered, 35 it will cause the body portion 35 of the car to assume a substantially horizontal position and will be maintained in this position until the wheels 38 on the uprights 36 engage and rest upon the portion 32 of the track 31. This will cause the open front 40 end of the car to be lowered and the material will be discharged therefrom as is more clearly shown in Fig. 5.

The counter-balance 30 together with the 45 weight 37 will maintain the parts normally in the position shown in Fig. 1, but when material is delivered into the car or receptacle 35 from the hopper 12, the material will cause the scale beam 21 to be overbalanced and will rock the scale beam together with the track or way 31 in a direction to lower the track or way. During this 50 operation the car or receptacle 35 will travel upon the track toward the outer end thereof and will continue to travel until the car is arrested in its movement by the stop 34 which will occur at about the time the track reaches the limit of its downward movement. This will deliver the material from 55 the car into any suitable receptacle provided for that purpose. When the car is emptied of the material, the weight 27 will over-balance the car and the scale beam will be moved in the opposite direction to raise 60 the track 31 and cause the car 35 to travel 65

by gravity down the track as it assumes an inclined position, until the car is arrested by the stop 34 on the track 31 which will occur when the parts assume the position shown in Fig. 1.

Obviously the weight 27 may be adjusted upon the scale beam to vary or control the amount of material which actuates the car.

Any suitable means may be provided for automatically shifting the cut-off 15 and 70 the receptacle 18, but inasmuch as in the present form of the invention the cut-off 15 and receptacle 18 are mounted upon the swinging support 16, there may be provided an arm 40 which may be connected 80 with the support 16 and which arm when the support 16 is in the position shown in Fig. 5 will, when the scale beam is moved to raise the track 31, stand within the path of movement of the car or receptacle 35 so 85 that as the car moves down the track or way 31 into the position shown in Fig. 1, it will strike the arm 40 and shift the support 16 to open the outlet 14 and close the outlet 13.

During the time that the car or receptacle 35 is being dumped and while the parts are in the position shown in Fig. 5, the cut-off 15 will be in a position to close the outlet 14 and open the outlet 13. In this position, it will be readily seen that a considerable amount of the material will be delivered from the hopper 12 into the receptacle 18, and when the car or receptacle 35 swings the parts to the position shown in Fig. 1, 100 the material which has been delivered into the receptacle 18 will be deposited into the car 35, causing a large bulk of the material to be quickly delivered to the car. As the car causes the cut-off 15 to close the opening 13, the smaller outlet opening 14 will be opened and will allow only a smaller and finer supply of material to be delivered to the car so as to obtain the exact weight 105 which will cause the loaded car to overbalance the weight 27 on the scale beam.

In order to maintain the car upon the track or way 31, a suitable guide 41 may be provided which is adapted to pass over the axles 42 of the wheels 38—39 and which 115 guide 41 is preferably arranged to coöperate with the body of the track 31 to maintain the axles therebetween.

If desired and in order to limit the swinging movements of the scale beam 21, suitable stops 43—44 may be provided which coöperate with the upright or support 22.

It is thought that the operation of this device will be clearly understood from the foregoing specification, and it will be clearly 125 seen that the apparatus will be automatic in its operation to automatically shift the car 35 to a loading and a dumping position for supplying material thereto so long as there is any material in the hopper 12. 130

Obviously all of the parts may be constructed of any desired material and of any suitable size and configuration, and while the preferred form of the invention has been 5 herein shown and described, it is to be understood that various changes may be made in the details of construction and in the combination and arrangement of the several parts, within the scope of the claims without departing from the spirit of this invention.

What is claimed as new is:—

1. Weighing scales embodying a supporting structure, a supply hopper mounted 15 thereon, said hopper having a discharge outlet, a pivotally mounted and counter-balanced scale beam, a weight adjustable upon the scale beam, a runway rigidly connected with the scale beam, a car freely movable 20 by gravity upon the runway in accordance with the pivotal movement of the scale beam, and means for controlling the said discharge outlet by the movement of the car upon the runway, said car being adapted 25 to be positioned to receive the material from the hopper.

2. Weighing scales embodying a supporting structure, a supply hopper mounted thereon, said hopper having a discharge outlet, 30 a pivotally mounted and counter-balanced scale beam, a weight adjustable upon the scale beam, a runway rigidly connected with the scale beam, a car freely movable by gravity upon the runway in accordance 35 with the pivotal movement of the scale beam, means for controlling the said discharge outlet by the movement of the car upon the runway, said car being adapted to be positioned to receive the material from the hopper, and 40 means for maintaining the body of the said car substantially horizontal during its travel upon the runway.

3. Weighing scales embodying a supporting structure, a supply hopper mounted 45 thereon, said hopper having a discharge outlet, a pivotally mounted and counter-balanced scale beam, a weight adjustable upon the scale beam, a runway rigidly connected with the scale beam, a car freely movable by 50 gravity upon the runway in accordance with the pivotal movement of the scale beam, and means for controlling the said discharge outlet by the movement of the car upon the runway, said car being adapted to be positioned 55 to receive the material from the hopper, one end of the car being open, a portion of the runway at one end being deflected to cause one end of the car to be lowered with respect to the runway to dump the car.

60 4. Weighing scales embodying a pivotally mounted counter-balanced scale beam, a weight adjustable on the beam, a runway rigidly extending from one end of the beam, a car movable by gravity upon the runway 65 in accordance with the pivotal movement of

the scale beam, means for delivering a supply of material to be weighed to the car, and means operable by the car when the latter reaches a predetermined point in its travel upon the runway for controlling the 70 supply of material to the car, a portion of the runway being shaped to cause the car to dump when it reaches another predetermined point in its travel upon the runway.

5. Weighing scales embodying a pivotally mounted counter-balanced scale beam, a weight adjustable on the beam, a runway rigidly extending from one end of the beam, a car movable by gravity upon the runway in accordance with the pivotal 80 movement of the scale beam, means for delivering a supply of material to be weighed to the car, means operable by the car when the latter reaches a predetermined point in its travel upon the runway for controlling the supply of material to the car, a portion of the runway being shaped to cause the car to dump when it reaches another predetermined point in its travel upon the runway, and means for maintaining the car against 85 accidental displacement with respect to the runway.

6. Weighing scales embodying a pivotally mounted counter-balanced scale beam, a weight adjustable on the beam, a runway 95 rigidly extending from one end of the beam, a car movable by gravity upon the runway in accordance with the pivotal movement of the scale beam, means for delivering a supply of material to be weighed to the car, 100 means operable by the car when the latter reaches a predetermined point in its travel upon the runway for controlling the supply of material to the car, a portion of the runway being shaped to cause the car to dump 105 when it reaches another predetermined point in its travel upon the runway, and means for maintaining the body of the car in a substantially horizontal position during its travel upon the runway.

7. Weighing scales embodying a pivotally mounted counter-balanced scale beam, a weight adjustable on the beam, a runway rigidly extending from one end of the beam, a car movable by gravity upon the runway 115 in accordance with the pivotal movement of the scale beam, means for delivering a supply of material to be weighed to the car, means operable by the car when the latter reaches a predetermined point in its travel 120 upon the runway for controlling the supply of material to the car, a portion of the runway being shaped to cause the car to dump when it reaches another predetermined point in its travel upon the runway, said 125 car embodying spaced uprights, and rollers connected with the uprights and movable along the runway, the forward uprights being of a greater length than the rear uprights.

8. Weighing scales embodying a supporting structure, a supply hopper mounted thereon, said hopper having a discharge outlet, a counter-balanced pivotally mounted scale beam, a runway rigidly connected with the beam, a car movable upon the runway in accordance with the pivotal movement of the scale beam and adapted to be dumped by the lowering of the runway, a delivery receptacle intermediate the hopper and the car and shiftable with respect to the hopper, means whereby the receptacle may be shifted by the movement of the car on the runway and means whereby the receptacle may be adjusted toward and away from the hopper for varying the amount of material delivered thereto from the hopper.
9. Weighing scales embodying a supporting structure, a supply hopper mounted thereon, said hopper having a discharge outlet, a counter-balanced pivotally mounted scale beam, a runway rigidly connected with the beam, a car movable upon the runway in accordance with the pivotal movement of the scale beam and adapted to be dumped by the lowering of the runway, a delivery receptacle intermediate the hopper and the car and shiftable with respect to the hopper, means whereby the receptacle may be shifted by the movement of the car on the runway, means whereby the receptacle may be adjusted toward and away from the hopper for varying the amount of material delivered thereto from the hopper, and a cut-off for controlling the outlet of the hopper, said cut-off being responsive in its operation to the operation of the said receptacle.
10. Weighing scales embodying a supporting structure, a supply hopper mounted thereon and having two discharge outlets of different sizes, a counter-balanced pivotally mounted scale beam embodying a runway rigidly connected with the beam, a car movable upon the runway in accordance with the pivotal movement of the scale beam and adapted to be dumped by the lowering of the runway, a cut-off coöperating with both discharge outlets and adapted to alternately close the said outlets, and means whereby the movement of the car upon the

runway will shift the cutoff to open one of the outlets and close the other.

11. Weighing scales embodying a supporting structure, a supply hopper mounted thereon and having two discharge outlets of different sizes, a counter-balanced pivotally mounted scale beam embodying a runway rigidly connected with the beam, a car movable upon the runway in accordance with the pivotal movement of the scale beam and adapted to be dumped by the lowering of the runway, a cut-off coöperating with both discharge outlets and adapted to alternately close the said outlets, means whereby the movement of the car upon the runway will shift the cut-off to open one of the outlets and close the other, and a delivery receptacle interposed between the car and the said outlets for receiving the material from the hopper to be delivered to the car, said receptacle being shiftable with the said cut-off.

12. Weighing scales embodying a supporting structure, a supply hopper mounted thereon and having two discharge outlets of different sizes, a counter-balanced pivotally mounted scale beam embodying a runway rigidly connected with the beam, a car movable upon the runway in accordance with the pivotal movement of the scale beam and adapted to be dumped by the lowering of the runway, a cutoff coöperating with both discharge outlets and adapted to alternately close the said outlets, means whereby the movement of the car upon the runway will shift the cutoff to open one of the outlets and close the other, a delivery receptacle interposed between the car and the said outlets for receiving the material from the hopper to be delivered to the car, said receptacle being shiftable with the said cut-off, and means whereby the receptacle may be adjusted toward and away from the hopper to vary the amount of material received thereby from the hopper before the receptacle is emptied.

In testimony whereof I have signed my name to this specification on this 26th day of January, A. D. 1920.

JONATHAN S. JONES.
